JULIAN A. CAMPBELL, OF LONG BEACH, CALIFORNIA

METHOD OF ABSORPTION

Application filed December 17, 1927, Serial No. 240,742. Renewed January 16, 1932.

This invention has to do with methods for transferring vapor between liquids and gases. Such methods are used, and the method of this present invention is capable of use, in absorption systems, or in stills, dephlegmators, and the like. In any such method or process, whether the immediate object is to take vapor out of the liquid, or to absorb vapors into a liquid out of gas, the general underlying function is one in principle; that is, to establish a condition of equilibrium between vapors and liquids, under the operating conditions maintained. Consequently, the method herein described is capable of use either in absorption systems or in distilling or dephlegmating systems; in fact, the major object of this invention, that of bringing liquids and gases into very finely divided and intimate contact with each other, applies equally well to all such systems. However, the invention is largely used in absorption systems; so, for that reason, and also because the invention will be readily understood in that connection, I explain the invention here as applied to absorption, and particularly absorption of low boiling point vapors, such as gasolene, which are carried in natural gas.

The method which is the subject matter of the present invention has some similarity to other methods which are subjects of co-pending applications filed by me. In my application Serial No. 184,870, filed April 19, 1927, entitled "Method of absorption", I set out a method characterized by the formation of a mass of froth in which a gas and liquid are brought into intimate contact and subsequently separated by breaking up the froth. Then, in my prior application, Serial No. 123,417, filed July 19, 1926, I have set out an apparatus and method wherein a mass of froth is first formed in a chamber between two perforated plates, the mass of froth being then forced through the upper perforated plate, by whose action the froth is rendered completely uniform, the froth mass building up above the upper perforated plate and being finally broken up at a level above that upper plate. In both these prior methods the intimate contact is obtained between the liquids and gases within the masses of froth, the breaking of the froth resulting in the direct formation of a body of separated liquid. In contradistinction to that method, or as an additive functional step, the present method first forms a mass of fine and uniform froth, obtaining intimate contact in such froth form; but then, in the present method, this froth is broken up in such a manner that the liquids and gases are not merely separated as before, but so that the liquids are broken up into very fine particles in an atmosphere of the gas. The froth thus not only serves in the first instance as a means of obtaining intimate contact, but also serves to get the liquid into the form of thin films, from which form the liquid is easily and effectively broken up into very fine particles which form a fine mist in the gaseous atmosphere and obtain a most highly intimate contact between the liquid and gas. How all of this is done will now be best understood from the following detailed specification wherein I explain first a suitable apparatus and then explain the method as carried on in this apparatus. It will be understood that the method is not necessarily limited to performance in the particular apparatus described, but as this apparatus includes the necessary characteristics and features for carrying on the method, and further, forms a simple, effective apparatus for that purpose, I shall describe the apparatus in detail. One of the apparatus features which, as far as now seen, is necessary for carrying on the method, is this: That the froth be broken up into mist at a level above which either any unbroken froth or coalescing liquid (resulting from separation of liquid and gas out of froth) may accumulate. That is, where the formed froth is specifically blown through the upper perforated plate, it is blown upwardly directly into an atmosphere of gas, and not blown upwardly into a mass of froth or a body of liquid. The apparatus hereinafter described provides the necessary physical feature for the stated operation. It will be understood, however, that the apparatus itself is not made the subject matter of the claims herein, the apparatus being claimed in a co-pending applica-

tion, Serial No. 240,741, filed on even date herewith and entitled "Absorber" (which matured into Patent No. 1,748,409 issued Feb. 25, 1930). Such apparatus is illustrated in 5 the accompanying drawings, in which:

Fig. 1 is a fragmentary vertical central section of the absorber;

Figs. 2, 3, 4 and 5 are horizontal cross-sections taken respectively on lines 2—2, 3—3, 10 4—4, and 5—5 of Fig. 1;

Fig. 6 is a perspective of one of the inner shell sections;

Fig. 7 is a perspective of another of the inner shell sections; and

15 Fig. 8 is an enlarged fragmentary vertical section in the nature of an enlargement of certain portions of Fig. 1.

In the drawings the numeral 10 designates an exterior shell which may be of any suitable form, usually cylindric and of a substantial height as compared with its diameter. Near the bottom of the shell there is a gas inlet 11 and a liquid outlet 12, the bottom of the shell usually containing a float 25 13 which acts to operate a valve controlling the liquid outlet (not shown, as it has no bearing on the present invention). Near the bottom of the shell there is an internal ring 15 having an upstanding inner flange 16 that forms an annular liquid holding channel around the periphery of the shell, for the purpose of forming a liquid seal at a point where the liquid is finally discharged into the bottom part of the shell, all as will hereinafter appear. This ring 15 also forms the supporting shelf which supports the several inner shell sections and the several superposed floors.

Briefly described, the shell and floor structure is made up of a series of outer shell sections 20 and 20a and a series of inner shell sections 21, 21a and 21b; with perforated floors 22 and 23, and an uppermost perforate floor 24, supported and spaced by the 45 several shell sections. The floors are preferably supported and spaced so that they are located in pairs, 22 and 23. The outer shell sections 20 and 20a are all imperforate, their function being merely to form an outer shell 50 wall for the passages which are located between such outer shell wall and the inner shell wall formed of sections 21 and 21a. Operatively and functionally the outer shell sections 20 and 20a may be regarded as the 55 outer wall of the double shell structure herein referred to, the outermost continuous shell 10 being provided only for the purpose of making the apparatus pressure-tight as a whole. Or the outermost continuous shell 60 10 may be looked upon as the outer shell of the double walled structure, the outer shell sections 20 being provided merely to make a wall, outside of which the assembly bolts may be passed. It is convenient to run those 65 assembly bolts through the edges of the sev-

eral floors, to hold the whole structure in aligned position, and it is also convenient to have the several floors extend their edges outwardly past the outer shell sections 20, 20a, as thereby certain perforations in the 70 several floors, registering with the spaces between the shell sections, may be utilized for controlling and directing the flow of liquid. And it is convenient to have the assembly bolts pass through the several floors outside 75 of the operating space between the double walls, as thereby it is not necessary to make tight joints where the bolts pass through the several floors. Consequently, in a preferred structure, in accordance with the present invention, the several floors 22 and 23 are of such diameters as to fit fairly snugly into the outermost main shell 10. The edges of these floors, outside the shell sections 20, have notches 25 which pass the vertical assembly 80 bolts 26, and the outer shell sections 20, 20a have circular ribs 20b that, bearing against the bolts, serve to center these shell sections.

The assembly bolts are secured at their lower ends to the ring 15 and, passing upwardly through the notched edges of all the floors, and also through the uppermost assembly ring 27, have nuts 28 at their upper ends, which, being screwed down on spacer tubes 29, compress the whole assembly tightly in a vertical direction and make sufficiently fluid-tight joints between the several floors and the edges of the several shell sections.

Each shell section 21 is provided with openings 35 near its lower edge, the openings extending around approximately half of the periphery. Each section has a plurality of spacer ribs 36 which do not extend to the lower edge of the section, and two oppositely disposed spacer ribs 37 which extend from top to bottom of the section. All the spacer ribs engage at their outer edges with the corresponding outer shell section 20 and serve to maintain the two concentric shell sections in proper relative position, and the two ribs 37 serve additionally to separate half of the annular space between the shell sections from the other half of said annular space. And the relative arrangement of opening and ribs is such that all of the openings 35 lie 110 in one of the half circumferences between the two ribs 37 and therefore communicate with only one of the half-annular spaces between the concentric shell sections.

The construction of the shell section 21a 120 is similar with openings 35a and ribs 36a and 37a, the only difference between sections 21 and 21a being a matter of height.

Each upper floor 23 has one or more raised perforated surfaces 43. In the particular design here shown these raised perforated surfaces 43 are formed as circular perforated plated plates raised on circular rims 44 above the surface of floor 23, each formation 43, 44, being in the form of an inverted pan with 130

a perforated top. These inverted pans are spaced apart from each other as shown in the various views so as to allow a considerable space around the pans for separated liquid to collect on the floor 23, the liquid collecting until it reaches a height sufficient to flow out through the openings 35. Each floor 23 also has peripherally arranged perforations 45 extending around its complete periphery and in such positions as to register with the annular space between the two concentric shell sections 20, 21 and 20a to 21a. Each lower floor 22 is preferably perforated over its entire surface within the circle of the shell section 21a, and outside the circle of that shell section 21a it has perforations 46 extending around half of its periphery only, these perforations registering with a half-annular space between the shell sections 20, 21, and 20a, 21a. The several floors 22 and 23 and the several shell sections 20, 21, 20a and 21a are all of identic construction, but are assembled in such a manner as to control and direct the flow of liquids as will now be described. The uppermost inner shell section 21b may be identic in structure with shell section 21, but is inverted, so that its openings 35b come near its upper edge rather than near its lower edge.

In operation as an absorber it will be understood the rich gas is fed under pressure into the lower end of shell 10, the gas passing upwardly through the several floors, and the denuded gas finally passing off through the gas outlet 50 at the top. At the same time, absorbing oil is being introduced through a suitable oil inlet, such as indicated at 51, the oil feeding through perforated distribution pipe 51a out over the uppermost perforated floor 24 and rising, as froth, to a level where the oil from broken froth overflows through openings 35b of shell section 35c of shell section 21b. Flowing through these openings the oil flows into a half annular space between shell section 21b and a corresponding concentric section 20, being restricted to that half annular space by the two ribs 37. The uppermost floor 24 has a semi-circular series of perforations 46a similar to the perforations 46 of floors 22; and the oil flows downwardly through these perforations 46a into the half annular space A immediately below and between the next lower shell sections 21 and 20. An absorber constructed in accordance with my invention may contain any suitable number of floor sets; but for the purpose of explanation, I will suppose that the upper set shown in Fig. 1 and in Fig. 8 is the uppermost set of the absorber. Thus, the oil will first flow down through the half annular space A between shell sections 20 and 21, at the right-hand side of Figs. 1 and 8, and thence the oil will flow through the perforations 45 of floor 23 into the half annular space B between

shell sections 20a and 21a and between floors 22 and 23. Thence the oil will flow directly through openings 35a into the space C inside shell section 21a and between the two floors 22 and 23. Here the oil, spreading out over floor 22, is picked up by the gas passing up through that perforated floor and a mass of froth is formed, this mass of froth rising and filling the inverted pans 43, 44 until the froth is forced up through the perforations in plates 43. The comparative aggregate perforations areas of floors 22 and 23 are preferably such that the velocities through the perforations are about equal. For instance, in an average case, the lower floor 22 has perforations 5/32" diameter on 1" spacings. The plates 43 of the upper floor have holes of the same diameter but on half-inch spacings. The total area of plates 43 is about half of the total area of a floor 22; so that the aggregate perforation area of an upper floor 23 is about twice the aggregate perforation area of the lower floor 22. But the lower floor passes gas only, while the upper floor passes both gas and liquid; and in an average case the velocities through the two floors is consequently somewhat near equality. The action at and above the lower floor is to form a mass of froth, the oil being frothed as completely as possible. This mass of froth moves up under the gas pressure and is forced through the upper floor perforations. At the upper floor perforations the froth bubbles are reduced to substantially uniform size, and any unfrothed gas and oil is formed into bubble formation. In other words, the first action at the upper plate perforations may be considered to be to make the froth more uniform, as a preliminary to disrupting the froth and atomizing the oil.

The velocity through the perforations—the expansion of the gas above the perforations—breaks up the froth bubbles and forms the oil into an exceedingly fine mist floating in the gas above the upper floor. This mist falls through the gas, the collecting liquid flowing down below the pan tops to collect on the floor 23 around the pans. Thence the oil flows out through the openings 35 at the left-hand side of shell section 21 into the half annular space D (see Fig. 8) between that shell section and shell section 20. Here the oil flows down through floor perforations 45, through space F between shell sections 20a and 21a and floors 23 and 22, and thence the oil flows through the floor perforations 46 at the left-hand side of floor 22 and into and through the half-annular space A¹ between the next lower shell sections 20 and 21. Half-annular space A¹ is the same as half-annular space A except that it is arranged at the opposite side of the assembly. The oil flows directly downwardly through space A¹ and on down through floor perforation 45 into the left-hand half-annular space

B¹ between the next lower shell sections 20a and 21a. Here the oil, stopped from further downward flow by part 22a of floor 22, flows again through openings 35a which, in this shell section 21a, are arranged at the left of the apparatus as shown in the drawings, the oil flowing into the circular space C¹ inside shell 20a between floors 22 and 23. The oil is here again subjected to the action of the upwardly flowing gas, the froth rising and being forced through perforated plates 43, the gas being freed to pass on up through the next perforated floor 22, and the atomized and collected oil flowing down around pan walls 44 onto the floor 23, and thence out through opening 35, at the right-hand side of shell section 21, into and through the half-annular space D1 at the right hand side of the assembly. Thence the oil flows down through floor perforations 45 and 46 and through right-hand half-annular space E1, and into right-hand half-annular space A₂. This space A₂ is an exact counterpart, both in structure and position, with the first mentioned half-annular space A; and the flow of the oil from here on down through the apparatus is repetitious of the flow now fully described. Upon leaving the last and lowermost floor set, the oil will pass through the openings 35, such as those shown at the lower left side of Fig. 1, and, passing through perforations 45 and 46 in those lowermost floors, will pass thence into space F (see Fig. 1 at the lower left) outside the lowermost shell section 21. Thence the oil passes through openings 35 in that lowermost shell section 21, over the seal flange 16, and drops down into the body of oil which normally stands in the bottom of shell 10. This final passage of the oil is indicated by the arrows at the lower left-hand side of Fig. 1.

The oil being formed into a fine mist above each floor, falls out of the gas rather slowly. Consequently, in operating at reasonable gas flow velocity a certain amount of the mist, but not a large proportion, is carried up with the gas through the next perforated floor 22 where it is merely caught by and merged in the froth being formed there. To prevent any oil mist being carried out of the apparatus above the uppermost floor 23 I have provided the uppermost perforated floor 24 (which is like floor 22 but without any associated floor 23). The incoming oil is first distributed in a thin layer over floor 24. The gas rises through that layer, forming and raising a mass of froth whose level rises to the lower edges of openings 35b. At the upper froth surface, and at the opening edges which are preferably sharp, the froth breaks up, freeing the gas to pass on up and out outlet 50 as substantially dry gas, the freed oil flowing through openings 35b to pass down through the apparatus.

From the foregoing description of opera-

tion of the various apparatus features, it will now be understood how the oil is substantially all formed into a froth with the gas in a space immediately above a perforated floor 22. It will be noted that the oil is delivered horizontally over the floor 22, being introduced to the floor at its edge and spreading out over the floor more or less in the form of a thin film or layer. Gas passing up through this thin oil layer forms the mass of froth which, in full operation, fills the space between the two perforated floors of a set. And the fact that the oil is delivered to the bottom of this mass of froth (rather than, for instance, being delivered by dropping down through the froth mass) prevents the inflowing oil from breaking up the froth mass. The result is thus the continuous formation and building up of a mass of froth, from below, at the perforated floor plate 22. This mass of froth is, above any selected floor plate, under a certain maintained pressure, due to the initial introduction of the laden gas under pressure at the bottom of the absorber. Under this pressure this mass of froth is forced up through the perforations in the raised plate 43 of the upper floor 23. At the perforations of plate 43 there is a certain drop of pressure, resulting in a substantial velocity of the froth mass through the perforations. (In practice, the pressures on the apparatus are maintained so that, as a typical instance, the drop in pressure at each perforated plate is about 0.2 pound per square inch.) When the froth is forced through the upper plate perforations, the action at and within the perforations is, to some extent at least, to make the froth bubbles of uniform size and to form into bubbles any comparatively larger mass of either gas or oil which might have escaped intimate frothing action at the lower perforated plate. Immediately upon escape of the froth above the upper plate perforations into the gaseous atmosphere above the upper plate, the froth bubbles burst, under the expansive action induced by the lowered pressure in the space above the upper plate. This action of breaking the froth bubbles may be looked upon as due to the velocity of the froth through the upper plate perforations; but it is immaterial whether the velocity or the reduced pressure be considered the cause of forth-breaking, as the relatively lower pressure is itself the cause of the velocity maintained.

In the gaseous atmosphere above the upper plate, the froth bubbles burst, the thin oil films breaking up into a multitude of very fine liquid particles—the oil becomes atomized to a very fine mist. This mist more or less floats in the gaseous atmosphere. To a large degree the mist slowly settles and coalesces to form a liquid body of oil which accumulates on the floor 23 below the level of plates 43. Also any slight amount of froth

which may remain unbroken after passage through the upper perforations accumulates at a level below the raised plates 43; so that neither the accumulated oil or froth interfere with the froth atomizing action. Thus, the froth atomizing action goes on unimpeded, the very fine atomized particles of oil more or less floating, or slowly sinking, in the gaseous atmosphere, and the coalesced liquid flowing off from the described lower level and thence down to the next pair of plates in the apparatus. This coalesced liquid body has been found in practice to be substantially free of gas, which is a highly desirable condition of operation. The liquid mist, however, is so fine that not all of its settles out of the gaseous atmosphere above the upper perforated floor, a small part of it being carried on up through the next perforated floor and into the next frothing action. This upward carriage of mist is not objectionable except at a point above the uppermost floor, where it is taken care of as has been before described.

I claim:

1. The method that includes first forming a froth of a liquid and a vapor laden gas, at a selected pressure, then expanding the froth in an atmosphere of the gas at a comparatively less pressure and thereby breaking the froth bubble-films into fine particles, there being an abrupt pressure change between the pressure at which the froth is formed and the pressure of the gaseous atmosphere in which the froth is broken up, and allowing the fine liquid particles to settle in the gaseous atmosphere and to coalesce into a body of liquid out of contact with the froth being introduced into the gaseous atmosphere.

2. The method that includes forming a body of froth by passing a vapor laden gas up through a perforated plate over which an absorbing liquid is introduced, building up the froth body by continuing such formation and forcing the froth body by pressure up through another perforated plate and directly into an atmosphere of gas thereabove and at a relatively lower pressure, and thereby breaking the froth films into fine particles, allowing the particles to settle in the gaseous atmosphere to form a liquid body, out of contact with the froth being introduced to the gaseous atmosphere, and withdrawing liquid from the liquid body.

3. The method of causing intimate contact between a gas and a liquid, that includes first forming a froth of the gas and liquid, reducing such froth to substantial uniformity in which substantially all the liquid and gas are frothed, allowing the froth-bubble-films to expand and break into fine liquid particles in an atmosphere of the gas, and then coalescing said liquid particles and separating the resultant liquid from both the gas and the froth.

4. The method of causing intimate contact

between a gas and a liquid, that includes first forming a froth of the gas and liquid at any certain pressure, reducing such froth to substantial uniformity in which substantially all the liquid and gas are frothed, allowing the froth bubbles to expand and break into fine liquid particles in an atmosphere of the gas at comparatively less pressure, and then coalescing the liquid particles into a body of liquid out of contact with the froth being introduced into the gaseous atmosphere.

5. The method that includes first forming a vertical series of froth bodies comprising a liquid and a vapor laden gas at selected pressures, then expanding each of the froth bodies into atmospheres of the gas at comparatively less pressures and thereby breaking the froth bubble-films into fine particles, there being abrupt pressure changes between the pressures at which the froth bodies are formed and the pressures of the gaseous atmospheres in which the froth bodies are broken up, allowing the fine liquid particles released from the froth bodies to settle in the gaseous atmospheres and to coalesce into bodies of liquid, and delivering each of the liquid bodies formed by the coalesced particles to the froth body next below to be reconverted into froth.

6. The method that includes forming a vertical series of froth bodies by passing vapor laden gas up through vertically spaced perforated plates over which absorbing liquid is introduced, building up froth bodies on said plates by continuing such formation and forcing the froth bodies by pressure up through other perforated plates and directly into atmospheres of gas thereabove at relatively lower pressures, and thereby breaking the froth films into fine particles, allowing the particles to settle in the gaseous atmospheres and to coalesce into liquid bodies, and delivering each of the liquid bodies formed by the coalesced particles to the froth body next below to be reconverted into froth.

In witness that I claim the foregoing I have hereunto subscribed my name this 28 day of November, 1927.

JULIAN A. CAMPBELL.
